BASKET FISHING TOOL

Harry Hanlon, Kettleman City, Calif.

Application January 27, 1936, Serial No. 61,098

1 Claim. (Cl. 294—86)

This invention relates to a basket fishing tool for removing from wells any objects which may be lost in the well, and has for the primary object the provision of a device of this character which may be either lowered into a well by a line or operated at the end of a rotating well drilling means and is so constructed that it will readily pass over an object at the bottom of a well and become gradually closed about said object by the weight thereon and moving against the bottom of said well, whereby the object will be trapped therein to permit the removal of said object from the well without danger of falling back into the well.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a side elevation, partly in section, showing a basket fishing tool arranged in a well prior to being closed about an object located at the bottom of the well.

Figure 2 is an end view illustrating the basket.

Referring in detail to the drawing, the numeral 1 indicates a tubular body of any desired length and diameter and has one end slightly reduced and screw threaded to receive a sleeve 2 for detachably securing the body to a coupling 3 employed in well drilling operations for connecting one device to another. Any other form of coupling may be connected to the body than that shown so that the body can be adapted to different types of well drilling means. The opposite end of the body 1 is cut or severed to form a plurality of tapering teeth 4. The teeth taper towards their free ends and each tooth has a

straight edge 5 and a beveled edge 6. The teeth progressively increase in length so that one tooth will be the first to contact the bottom of a well when lowered therein, as shown in Figure 1, and as this tooth bends the next longest tooth contacts the bottom of the well and bends and so on until all the teeth have been bent. The teeth are caused to progressively bend as they contact the bottom of the well by the weight of the body 1 and the lowering means connected thereto. The bending of the teeth is in the direction of each other to form a closure for the lower end of the body. The beveling of the teeth above referred to assures the teeth bending inwardly when contacting the bottom of the well with the weight of the body and lowering means thereon.

In operation, the body 1 is lowered into the well in any well known manner until the longest tooth contacts the bottom of the well. This positions the body over an object at the bottom of the well, as shown in Figure 1, and allowing weight to be placed on the body 1, and with a rotary motion to the body the teeth will be progressively bent inwardly towards each other with the object trapped in the body so that on the elevation of the body from the well, the object will be removed therewith.

Having described the invention, I claim:

A basket fishing tool comprising a tubular body, means for connecting said body to a lowering device, a plurality of spaced bendable circularly arranged teeth formed on the body and each tapering towards its free end and each having a straight edge and a beveled edge, said teeth progressively increasing in length to permit first one tooth after another to come in contact with the bottom of the well as the preceding tooth bends inwardly about an object to trap said object in the body.
